UNITED STATES PATENT OFFICE

CHESTER W. CRUMRINE, OF ROCHESTER, NEW YORK, ASSIGNOR TO ELECTROMATIC TYPEWRITERS, INC., OF ROCHESTER, NEW YORK, A CORPORATION OF NEW YORK

PERFORATING MACHINE

Application filed September 11, 1930. Serial No. 481,214.

This invention relates to improvements in perforating machines, and especially to machines of this kind which are employed for perforating master sheets used for controlling the operation of typewriting machines or other machines controlled by means of a master sheet of this kind.

In the operation of typewriting machines by master sheets in which extreme rapidity is desirable, when two adjacent type bars are operated in rapid succession, it frequently happens that the second type bar moves into the path of the first before the latter has returned from its printing position. When this happens, the second type bar strikes the first and cannot reach the printing position. When the type bars are more widely separated from each other, the angle between them at the printing point is wider and their paths overlap each other for a shorter distance so that a return movement of the first through only a short distance is necessary to withdraw it from the path of the second. The successive perforations in master control sheets for such machines are usually as close together as possible so that when adjacent type bars are to be operated by such sheets, the second frequently fails to print.

It is the object of this invention to provide a perforating machine on which the master sheet is made with simple and inexpensive means for preventing the formation of a second adjacent perforation until after the sheet has been advanced a second space, thus providing a wider space distance between the adjacent perforations corresponding to a longer time interval between the successive actuations of the adjacent type bars in the machine in which the sheet is to be used.

Another object of the invention is to provide a perforating machine of this kind with means for locking the adjacent keys against operation when a key is actuated, said locking means being automatically released when a space key or other non-adjacent key is actuated.

To these and other ends, the invention consists in the construction and arrangement of parts that will appear from the following

description when read in conjunction with the accompanying drawing, the novel features being pointed out in the claims at the end of the specification.

In the drawing:

Fig. 1 is a transverse section of a perforating machine illustrating one embodiment of the invention;

Fig. 2 is a fragmentary plan view of a portion of the keyboard of the same;

Fig. 3 is a fragmentary front elevation of a portion of the keyboard, parts being removed to expose underlying parts, and

Fig. 4 is an enlarged fragmentary detail view of the locking devices.

Referring particularly to the drawing in which similar references refer to the same parts in all the views, and in which one possible embodiment of the invention is illustrated applied to a power driven perforating machine of well known type, said machine comprises a die 1 having a plurality of openings in its front side with which the perforating punches 2 cooperates to perforate a work sheet 3 arranged on the die. The work sheet is supported in a paper apron 4 arranged beneath the die and supported on a fixed part from which it is directed upwardly over the front of the die and the openings therein to a feed roller 5 having a ratchet 6 fixed thereto which is engaged by devices presently to be described for turning the roller step by step to move the work sheet forwardly to space the perforations produced by the punches longitudinally thereof.

The punches 2 are slidably mounted in guideways provided therefor in a punch guide 7 and at their forward ends are operatively connected with the upper ends of levers 8 pivoted on a rod 9 extending across the machine and mounted on the punch guide 7. At their lower ends each of the levers 8 is bifurcated at 10 to provide a slot whereby it is operatively engaged by a laterally projecting stud 11 on a bell crank lever 12 pivoted on a rod 13 also extending across the machine. The lever 12 has an arm 14 to which the upper end of a link 15 is pivoted, the other end of said link being pivoted to an arm 16 of a bell crank lever pivoted at 17 to the frame of the

machine. The other arm 18 of the bell crank projects downwardly from its pivot and at its end carries a cam 19 revolvably mounted thereon and arranged adjacent the surface of a power driven roller 20. The cam 19 has a reentrant portion which normally faces the roller and is arranged closely adjacent its surface but out of contact therewith, in which position the cam is maintained by a stop lever 21 pivoted on the bell crank and has its lower end arranged in the path of a stop on the cam. Said lever has an offset portion 22 at its other end which is engaged by the bifurcated end 23 of an arm 24 on a key lever 25 also pivoted on the shaft 13.

The lever 21 has two offset portions 21^a and 21^b on its lower end which are spaced from each other, one of which, 21^a, is normally in the path of the stop on the cam. When the key lever is actuated to swing the lever 21, the offset portion 21^a moves from the stop and releases the cam, while the other offset portion 21^b moves into the path of the stop to arrest the cam, if the key lever be held depressed. When the cam is released, it is moved forwardly into frictional engagement with the roller 20 under the action of a spring-pressed finger 27 pivoted on the bell crank and engaging a lug or projection 28 on the cam. The cam 19 is rotated by its engagement with the driven roller 20 and as it rotates swings the bell crank on its pivot 17 and the lever 12 through the link 15 to actuate the lever 8 to move the punch toward the die to perforate the sheet thereon. A spring 30 connects the key lever 25 with a fixed part and resiliently maintains it and the parts connected therewith in normal position, shown in Fig. 1 of the drawing, and a spring 31 connects the bell crank lever 12 with a fixed part and resiliently maintains the lever 8 in retracted position with its stop arm 32 in engagement with the punch guide.

The bell crank levers 12 have rearwardly projecting arms 33 which engage a universal bar 34 extending across the machine and pivoted at 35 on the frame of the machine. The universal bar 34 has a rearwardly extending arm 36 pivotally connected with one end of a link 37, the other end of which is pivoted to an arm 38 pivotally mounted on the shaft 39 of the feed roller 5. A pawl 40 is pivotally mounted on the arm 38 and resiliently engages the teeth of the ratchet 6 under the action of the spring 41 which connects the pawl with the arm 38. A spring 42 is connected with the arm 36 at one end and has its other end anchored on the frame of the machine and is operative to move the link 37 and turn the arm 41 into engagement with a stop 43 secured in a fixed part of the machine. When a key 44 is operated to depress a key lever 25, the power operated devices are set in motion, as previously explained, to actuate the bell crank lever 12 to operate one of the

punches 2. At the same time, the universal bar 34 is actuated against the tension of the spring 42 and swings the arm 38 away from the stop 43 and retracts the pawl 40 over a tooth of the ratchet wheel. When the bell crank 12 returns to normal position under the action of the spring 31, the punch 2 is retracted from the work piece and the universal bar is released to permit the spring 42 to swing the arm 38 and with it the pawl 40 to turn the feed roller and advance the work sheet.

When two perforations are formed in the master sheet by the same punch in close proximity to each other, the second perforation is liable to pass the parts designed to be operated thereby before they return to normal position after actuation by the first perforation, with the result that the second perforation fails to actuate said parts. To overcome this liability, means are provided for locking the punch keys depressed when actuated. Said means comprises a locking bar 46 extending across the front of the keyboard and having rearwardly and downwardly extending arms 47 at its ends whereby it is pivoted to the frame of the machine. The upper edge of the bar 46 is bent rearwardly to form a lip adapted to engage cut-away portions 48 formed in the front ends of the key levers 25. A spring 49 connects the arm 47 with a fixed part and operates to maintain the lip on the locking bar resiliently engaged with the cut-away portions in the front of the key levers. At their upper ends, the cut-away portions are provided with upwardly and forwardly inclined walls 51 which are adapted to engage the lip on the locking bar when the key lever is depressed and said bar forwardly against the action of its spring, which spring moves the locking bar to engage its lip over the bar and locks or retains the bar in depressed position, thus preventing a second successive actuation thereof. The key lever is retained in this depressed position until a second key lever 25 or a spacing key, is depressed, either of which actuates the spacing devices to feed the sheet forwardly and the locking bar 46 to release the previously actuated key lever and permit its spring 30 to return it to normal position, when it may be actuated again to perforate the sheet.

As previously stated, it is also desirable to lock the adjacent keys against actuation when a key is depressed until the work sheet is advanced one or more spaces, since too rapid actuation of adjacent type bars in a typewriting machine in which the perforated sheet is to be used is to be avoided. As usual in this type of machine, the key levers are guided at their front ends in vertical slots 53 in a comb 52 extending across the front of the keyboard and secured to the frame of the machine. The slots 53 in the comb are spaced uniform distances apart, corresponding to the horizontal

spacing of the key levers. Suspended on the sides of the comb are locking devices 54 which swing to a normal position under the force of gravity. The locking devices 54 are sectorial in form, and when in the normal position project over adjacent slots 53 into the paths of the adjacent key levers, so that when one of said key levers is depressed, the locking devices in its path are cammed by the key levers and swung laterally thereby toward the paths of the adjacent key levers, and the descending key moves into the path of the locking devices and retains them in the paths of the adjacent key levers and prevents actuation thereof. The depressed key lever is retained in its depressed position by the locking bar 46 which is moved to release the key lever when another key or the spacing key is actuated, as previously explained.

Since the key levers are arranged as closely together as possible, the slots in the comb are also arranged very closely together, and the locking devices are arranged alternately on opposite sides of the comb so that they are free to swing laterally in opposite directions without engaging the adjacent locking devices. By this arrangement, each of the locking devices normally lies in the paths of both of the key levers between which it is pivoted, and two adjacent locking devices on opposite sides of the comb are normally arranged to swing into and out of the path of each of the key levers. A locking member 56 is arranged beneath all of the key levers and locked in engagement therewith by a member 55 controlling means which connects the driven roller 20 with power devices, such as an electric motor. When the driven roller is silenced, the key levers are locked against actuation.

Although only one embodiment of the invention is shown and described herein, it will be understood that this application is intended to cover such changes or modifications as come within the spirit of the invention or scope of the following claims.

I claim:

1. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for retaining any of said key levers depressed when operated to actuate a punch, locking devices arranged in the path of one of said key levers and movable into the path of adjacent key levers when said key lever is depressed for locking said adjacent key levers in normal position while other key levers are free to be operated, and means on another of said key levers for releasing said retaining means.

2. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for retaining any of said key levers depressed when operated to actuate a punch, a pair of locking devices arranged in the path of one of said key levers and movable in opposite directions therefrom when said key lever is depressed to lock immediately adjacent key levers against actuation while the first key lever is depressed and other key levers are free to be operated, and means on another of said key levers for releasing said retaining means.

3. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for retaining any of said key levers depressed when operated to actuate a punch, a slotted guide comb in which said key levers are guided, independently operable locking devices pivoted on said comb between adjacent slots and movable by gravity to a normal position projected into the paths of adjacent key levers, cams on said locking devices adapted to be engaged by one of said key levers when depressed to move the locking devices in opposite directions from its path and engaged by the key lever when so depressed for retaining the locking devices out of its path and in the paths of the immediately adjacent key levers to lock the latter against actuation, and means for releasing said retaining means when another key is depressed to operate the sheet feeding means.

4. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for retaining any of said key levers depressed when operated to actuate a punch, a slotted guide comb in which said key levers are guided, locking devices pivoted alternately on opposite sides of said guide comb between the slots and projecting into the paths of the adjacent key levers, cams on said locking devices adapted to be engaged by said key levers when depressed to move a locking device on each side of said comb from its path and engaged by the key lever when so depressed for retaining the locking devices out of its path

and in the paths of the immediately adjacent key levers to lock the latter against actuation, and means for releasing said retaining means when another key is depressed to operate the sheet feeding means.

5. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for compelling the depression of a key to feed the work sheet between successive alternate depressions of keys immediately adjacent each other, said means comprising a slotted comb in which the key levers are guided, locking devices on said comb between adjacent slots and projecting into the paths of the adjacent key levers and movable out of the path of one of said key levers when depressed and retained thereby in the path of adjacent key levers to lock said adjacent key levers against actuation, retaining means for locking the key in depressed position, and means on another of said key levers for releasing said retaining means.

6. In a perforating machine, the combination of a die, means for feeding a work sheet thereover, punches cooperating with the die to perforate the work sheet, key levers operatively connected with said punches, means operatively connected with said key levers for actuating the sheet feeding means to space the perforations in the work sheet, means for retaining any of said key levers depressed when operated to actuate a punch, a slotted comb in which said key levers are guided, locking devices movably mounted on said comb between adjacent key levers and projecting into the paths of said key levers, cams on said locking devices adapted to be engaged by said key levers when depressed to move the adjacent locking devices from their path and retain said locking devices in the paths of the immediately adjacent key levers while depressed to lock said adjacent key levers against actuation, and means for releasing said retaining means when another key is depressed to operate the sheet feeding means.

7. In a perforating machine, the combination of a die, means for feeding a work sheet thereover, punches cooperating with the die to perforate the work sheet, key levers operatively connected with said punches, means operatively connected with each of said key levers for actuating the sheet feeding means to space the perforations in the work sheet, means for compelling the depression of a key lever to feed the work sheet between successive depressions of the same key and successive alternate depressions of immediately adjacent keys, said means comprising a device for retaining any of said key levers depressed

when operated to actuate a punch, independently operable locking devices in the paths of said key levers and movable from the path of a key lever when depressed and retained by said key lever in the paths of the immediately adjacent key levers to lock them against actuation while said key lever is depressed, means on another of said key levers for releasing said retaining device when any one is actuated to perforate and space the work sheet, and a space key for releasing said retaining device and spacing the work sheet independently of the perforating devices.

In witness whereof, I have hereunto signed my name.

CHESTER W. CRUMRINE.
